CLAIM

The ornamental design for a baseball and softball training device, as shown and described.

DESCRIPTION

FIG. 1 is a front perspective view of a baseball and softball training device showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is an exploded view thereof.

The broken lines in the drawings represent numbers 1-9 over the baseball or softball of the device, which forms no part of the claimed design.

1 Claim, 8 Drawing Sheets
